US00D957552S

(12) **United States Design Patent** (10) **Patent No.:** **US D957,552 S**
(45) **Date of Patent:** **** Jul. 12, 2022**

(54) **EXERCISE STRAP**

- (71) Applicant: **Ken Schmidt**, Los Angeles, CA (US)
(72) Inventor: **Ken Schmidt**, Los Angeles, CA (US)
(**) Term: **15 Years**
(21) Appl. No.: **29/752,847**
(22) Filed: **Sep. 29, 2020**
(51) LOC (13) Cl. **21-02**
(52) U.S. Cl.
USPC **D21/694**
(58) **Field of Classification Search**
USPC D21/662, 685, 683, 692, 694, 691;
D24/192
See application file for complete search history.

(57) **CLAIM**

The ornamental design for an exercise strap, as shown and described.

DESCRIPTION

FIG. 1 is a perspective front view of the exercise strap, which embodies my design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the claimed design shown in use thereof;

FIG. 9 is a perspective view shown with the handles inward thereof;

FIG. 10 is a front view of FIG. 9 thereof;

FIG. 11 is a rear view of FIG. 9 thereof;

FIG. 12 is a left side view of FIG. 9 thereof;

FIG. 13 is a right side view of FIG. 9 thereof;

FIG. 14 is a top view of FIG. 9 thereof; and,

FIG. 15 is a bottom view of FIG. 9 thereof.

The broken lines shown in the figures are solely to show environment, and form no part of the claimed design.

1 Claim, 7 Drawing Sheets
